(57) **CLAIM**

I claim the ornamental design for an animal harness, as shown and described.

DESCRIPTION

FIG. 1 is a right side perspective view of an animal harness showing my new design, with straps arranged in an in use position;

FIG. 2 is a top plan view thereof with straps disconnected; FIG. 3 is a bottom plan view thereof with straps arranged as if it were on an animal;

FIG. 4 is a bottom plan view thereof with straps disconnected; and,

FIG. 5 is a top plan view thereof with straps disconnected. The broken lines represent claimed stitching.

1 Claim, 2 Drawing Sheets(56)
